WARM AIR FURNACE

Allen P. Livar, Dayton, Ohio, assignor to Chrysler Corporation, Detroit, Mich., a corporation of Delaware

Application March 14, 1940, Serial No. 323,909

12 Claims. (Cl. 126—99)

The present invention pertains to the construction of a warm air furnace, with particular regard to the provision of means for mounting and aligning the heavy heat exchanging surfaces of the furnace in the jacket of the furnace. The invention is of utmost utility in the construction of a gas-fired furnace since the nature of the flue gases from gas flames is such as to make it advisable to use cast iron heating sections which are less subject to corrosion than sheet metal heating sections, although it will be perfectly obvious that other types of fuels may be used in a furnace of the present invention and that other metals than cast iron may be used in the heat exchanging surfaces.

The principal object of the present invention is to devise heat exchanging means of singular efficiency in order that the weight of the heat exchanging means may be reduced to a minimum in spite of the fact that it is made of a heavy metal such as cast iron. Another object of the present invention is to provide means to support and align a heavy heat exchanger assembly at such a height above the floor as to permit the introduction of air from a blower means beneath the heat exchanger assembly. Another object of the present invention is to devise the heat exchanger assembly so as to provide the same with a curved bottom wall such that the air introduced beneath the heat exchanger assembly will be evenly divided around the bottom of the assembly.

In connection with the provision of means for supporting and aligning a heat exchanger assembly having a curved bottom wall, it is an object of the present invention to provide supporting and aligning means which automatically align the heat exchanger assembly with the remainder of the furnace so that expensive jigs or fixtures need not be provided for the purpose of assembling the furnace. It is an object of the invention to form such supporting and aligning means so as to be easily assembled without the aid of expensive jigs or fixtures for the manufacture of the supporting and aligning means.

It is a further object of the present invention to form the supporting and aligning means as a unitary structure having associated therewith rigid members serving as alignment guides and tip-limiting abutments, between which a portion of the heat exchanger assembly may be placed and instantaneously aligned in a vertical direction, and which also act to prevent tipping of the heat exchanger assembly beyond a very slight degree from vertical during the life of the furnace.

These and other objects and advantages of the present invention should be readily apparent from the following specification taken in connection with the accompanying drawings wherein like numerals refer to like parts throughout.

In the drawings, Fig. 1 discloses a vertical section through the front end of the furnace of the present invention, taken substantially along line 1—1 of Fig. 2;

10 Fig. 2 is a vertical section taken at right angles to the plane of Fig. 1 and substantially along line 2—2 of Fig. 1, the figure being on a slightly reduced scale;

15 Fig. 3 is a vertical section of the rear end of the furnace, taken substantially along line 3—3 of Fig. 2; and,

Fig. 4 is a view, substantially similar to Fig. 1, of a modified form of furnace having a plurality of heat exchanger assemblies mounted therein.

Referring to Figs. 1, 2, and 3, there is disclosed a furnace comprising an enclosing jacket 20, and front and rear, vertical partitions 21 and 22, respectively, dividing the interior of the furnace into an air entrance compartment 23 at the rear of the furnace, a heat exchanger compartment 24 in the intermediate portion of the furnace, and a front compartment 25. Air is admitted to the entrance compartment 23 through an opening 26 in the top wall of the jacket and drawn through filters 27 by blower means 28, mounted in the bottom of the compartment on legs 29 provided with resilient feet 30, and driven by a motor 31. The air is forced into the lower portion of the heat exchanger compartment 24 through the blower outlet 35 and between the rear legs 36 and front legs 37 of the supporting and aligning means 40. The air flows upward through the compartment 24 in contact with the surfaces of the heat exchanger assembly 41 and leaves the furnace jacket through an opening 42 in the top wall of the furnace. The openings 26 and 42 are preferably flanged for connection of the jacket to duct work.

45 The heat exchanger assembly 41 preferably comprises a plurality of identical, substantially symmetrical with respect to the vertical center plane, sections 45 which are provided with complementary internal openings, forming passages for the gases of combustion, and complementary 50 external surfaces, forming passages for the flow of air across the surfaces heated by the gases of combustion. Each section includes walls 46 rising from a lower firebox portion 47 having a curved bottom wall 48. In the central upper portion of each wall 46 there is provided a protrud-

ing flange 49, the flanges of adjacent sections forming, together with the sealing rings 50, a gas passage in communication with the spaces between the walls 46 and the interiors of the firebox portions and with the interior of a stack connector 51 extending through the partition 22, into the compartment 23 and laterally through a side wall of the jacket. The stack connector 51 is fastened to the rear opening of the rear section 45 by tie-rods 52 extending through the communicating openings and a cap 53 sealing the front opening of the front section 45. The fire box portions 47 are provided with flanges which, together with sealing bands 55, rear plate 56, and front plate 57 form a firebox into which the gas burner 58 or other flame-producing means is introduced.

The upper portions of the sections 45 are preferably wider than the firebox portions so as more completely to fill the space between the side walls of the jacket, and baffles 60 extending inward from the side walls of the jacket direct the air rising around the lower portions of the assembly into the spaces between the walls 46 of adjacent sections. The walls 46 are preferably provided with a plurality of integral heat exchanging pins 61, preferably arranged in staggered rows so as to cause the air to follow tortuous courses in contact with the pins and the walls, as shown by full-line arrows. Preferably those of the pins in the central portion of the walls are matched by integral baffle rods 62 extending between the walls 46 of each section so as to cause the gases of combustion to impart more heat to the walls and pins 61. Also, it is preferable that an arcuate baffle 63 extend between the walls 46 substantially in line with the lower parts of flanges 49 so as to cause the flue gases to rise into the upper, outer corners of the heat exchangers before travelling horizontally into the stack connector 51, as shown by broken-line arrows.

The plates 56 and 57 are joined by tie-rods 65, 66, 67, and 68, at least two of which, tie-rods 65 and 68, extend horizontally and externally of the assembly above the curved bottom walls 48. Mounting bolts 70 and 71, extending forward from plate 57, support a mounting plate 72 which is sealed to a flange 73 extending forward from plate 57 through partition 21, and which provides a support for the venturi 75 of the gas burner, the pilot tube 76, an inspection door 77, and other devices commonly associated with a gas burner. The tops of each section 45 may be provided with lugs 80 between which may be placed a humidifier pan 81. Suitable controls for the furnace (not shown) may be mounted in the compartment 25 and the jacket may be provided with access doors (not shown) wherever desired.

The heat exchanger assembly is obviously too heavy to be supported by the partitions 21 and 22 unless such partitions were made of such heavy materials as to be impractical. Accordingly, the supporting means 40 is designed to carry the entire weight of the heat exchanger assembly 41, the heat exchanger assembly being mounted and aligned in the supporting means 40 and the jacket then placed about the combined units. The jacket preferably rests upon the floor and preferably has very little contact with the heat exchanger assembly so that it may be shifted slightly after assembly.

The supporting and aligning means 40 comprises the legs 36 and 37, previously described, lower, horizontal braces 85 connecting the bot-

toms of legs 36, and 86 connecting the bottoms of legs 37, and upper braces 87 and 88 running longitudinally of the assembly between the front and rear legs and connected thereto by gusset plates 89. The legs extend upward above the longitudinal braces 87 and 88, and vertical plates 90 and 91 at the front and rear, respectively, are welded to the upright extensions thereof. Each plate is provided with a V-shaped upper edge adapted to cradle a curved bottom wall 48 of one of the sections 45, with the sides of the V-shaped edges tangentially in contact with the curved bottom wall. The angularity of the V is preferably such as to make the points of contact equally spaced from the center plane of the heat exchanger assembly so as to give some lateral support in addition to supporting the entire weight of the heat exchanger assembly, and so as to cause the heat exchanger assembly to slide into horizontal alignment when rested thereon.

The four legs continue on beyond the curved bottom wall and terminate at such heights with respect to the tangential points of contact of the curved bottom wall and the V-shaped edge of plates 90 and 91 as to be beneath and closely adjacent, but preferably not touching, the tie-rods 66 and 68 adjacent the ears through which the tie-rods pass.

This construction permits the manufacture of a heat exchanger assembly having somewhat loose tolerances and the manufacture of a supporting structure and jacket having equally loose tolerances. The V-shaped edges of plates 90 and 91 are cut fairly accurately so that if the bottom wall of the section were accurately machined the heat exchanger assembly would align itself in the supporting cradle. However, since cast iron is hardly ever true, the rigid, upper ends of the legs of the supporting structure serve as aligning fixtures which the assembly crew may observe to see that the heat exchanger assembly is vertically aligned. No fastening means are necessary for field assembly since the heat exchanger assembly is cradled in the supporting and aligning structure, and the tops of the legs prevent serious tipping of the heat exchanger assembly by abutting the tie-rods in the event that the heat exchanger assembly tips toward one side or the other.

Fig. 4 discloses a modification of the present invention wherein a plurality of heat exchanger assemblies 41 are cradled side by side in a modified supporting and aligning structure 40'. In this instance the supporting and aligning structure comprises a structure including vertical, front legs 37', vertical, rear legs (not shown) and cross braces as indicated. A modified vertical plate 90' is provided with a plurality of equal, V-shaped notches in its upper edges adapted to cradle, space, and align the heat exchanger sections. The plate 90' is welded to substantially vertical, rigid members 100 and 101 forming a pair of aligning and tip-limiting abutments for one heat exchanger, and rigid members 102 and 103 forming a second pair for the other heat exchanger assembly. Plate 90' may be matched by a similar rear plate (not shown) and the rigid members may be matched by a similar rear member (not shown). It is also preferable that the baffles 60, mounted on the jacket walls, be supplemented by a central baffle 60' adapted to direct air from the center toward the sides of the compartment 24.

It is obvious from inspection of Fig. 1 that the

present construction permits of limitless alteration in capacity without material change in the principal parts. For example, a single heat exchanger section 45 may be used to form a very small furnace by mounting plates 56 and 57 on opposite flanges of the section and by attaching stack connector 51 to the rear of the single section. Similarly, heat exchanger assemblies comprising any other reasonable number of sections 45 may be built up as shown. In the case of a single-section heat exchanger assembly it would probably be sufficient to include only the front supporting plate 90 and the extensions of the front legs 31, or the rear supporting plate 91 and the extensions of rear legs 36, permitting the opposite end of the assembly to rest upon a simple, supporting member on the frame 40. Similarly, if a greater number of sections were built up to form a longer heat exchanger assembly, a greater number of supporting plates and extensions than shown might be used in the supporting assembly. As seen in Fig. 4 a plurality of heat exchanger assemblies may be utilized so as to limit the length of the furnace to a reasonable limit by using a plurality of heat exchanger assemblies in side by side relationship in a wider furnace, in which case it may be preferable so to space the supporting structure legs as to cause them to serve as braces for the side walls of the jacket.

In the foregoing specification and in the following claims I use the term "cast iron" to indicate the preferred material for construction of the heat exchanger sections. It is obvious that any material, such as welded steel plates, may be substituted therefor without the exercise of invention; and the use of the term "cast iron" is only meant to emphasize the singular utility of the invention in connection with a heat exchanger assembly of a material having relatively great weight.

It is also obvious that the present invention could be adapted to the burning of other types of fuels, the disclosure being of a gas-fired furnace since the use of cast iron or heavy steel plate is particularly associated with the use of gas as a fuel. Other types of burner may be associated with the structure without the exercise of invention.

Having described preferred embodiments of the invention it should now be apparent to those skilled in the art that the same permits of modifications in arrangement and detail. All such modifications as come within the scope of the following claims are considered to be part of my invention.

I claim:

1. A warm air furnace comprising a heat exchanger assembly, said heat exchanger assembly being substantially symmetrical with respect to a vertical, longitudinal plane, and including an externally curved bottom wall substantially symmetrical to said plane, and means to support and align said heat exchanger assembly in the furnace comprising a frame including a vertical plate having a V-shaped notch in its upper edge to cradle the curved bottom wall of said heat exchanger assembly with the sides of the notch contacting said curved bottom wall substantially tangentially at points equally spaced from said plane.

2. A warm air furnace comprising a heat exchanger assembly, said heat exchanger assembly being substantially symmetrical with respect to a vertical, longitudinal plane, and including an

externally curved bottom wall substantially symmetrical to said plane, and means to support and align said heat exchanger assembly in the furnace comprising a frame including a plurality of vertical plates each having a V-shaped notch in its upper edge to cradle the curved bottom wall of said heat exchanger assembly with the sides of the notch tangentially contacting said curved bottom wall at points equally spaced from said plane.

3. A warm air furnace comprising a heat exchanger assembly, said heat exchanger assembly being substantially symmetrical with respect to a vertical, longitudinal plane, and including an externally curved bottom wall substantially symmetrical to said plane, and means to support and align said heat exchanger assembly in the furnace comprising a frame including a vertical plate having a V-shaped notch in its upper edge to cradle the curved bottom wall of said heat exchanger assembly with the sides of the notch contacting said curved bottom wall substantially tangentially at points equally spaced from said plane, and a pair of upright, rigid members each extending above a point of contact of said plate and bottom wall and terminating adjacent a portion of said assembly to serve as a vertical alignment fixture and tip-limiting abutment.

4. A warm air furnace comprising a heat exchanger assembly, said heat exchanger assembly being substantially symmetrical with respect to a vertical, longitudinal plane, and including an externally curved bottom wall substantially symmetrical to said plane, and means to support and align said heat exchanger assembly in the furnace comprising a frame including a plurality of vertical plates each having a V-shaped notch in its upper edge to cradle the curved bottom wall of said heat exchanger assembly with the sides of the notch tangentially contacting said curved bottom wall at points equally spaced from said plane, and a plurality of pairs of upright, rigid members, each pair of members extending above the points of contact of one of said plates and the bottom wall contiguous thereto and terminating adjacent portions of said assembly to serve as vertical alignment fixtures and tip-limiting abutments.

5. A warm air furnace comprising a heat exchanger assembly, said heat exchanger assembly being substantially symmetrical with respect to a vertical, longitudinal plane, and including an externally curved bottom wall substantially symmetrical to said plane and external abutment members above said curved bottom wall on each side of the heat exchanger assembly, and means to support and align said heat exchanger assembly in the furnace comprising a frame including a vertical plate having a V-shaped notch in its upper edge to cradle the curved bottom wall of said heat exchanger assembly with the sides of the notch contacting said curved bottom wall substantially tangentially at equally spaced points from said plane, and a pair of upright, rigid members each extending above a point of contact of said plate and bottom wall and terminating closely adjacent and below one of said abutment members to serve as a vertical alignment fixture and to coact with said abutment member to limit tipping movement of said heat exchanger assembly.

6. A warm air furnace comprising a heat exchanger assembly, said heat exchanger assembly being substantially symmetrical with respect

to a vertical, longitudinal plane, and including an externally curved bottom wall substantially symmetrical to said plane and external abutment members above said curved bottom wall on each side of the heat exchanger assembly, and means to support and align said heat exchanger assembly in the furnace comprising a frame including a plurality of vertical plates each having a V-shaped notch in its upper edge to cradle the curved bottom wall of said heat exchanger assembly with the sides of the notch contacting said curved bottom wall substantially tangentially at equally spaced points from said plane, and a plurality of pairs of upright, rigid members, each pair of members extending above the points of contact of one of said plates and the bottom wall contiguous thereto and terminating closely adjacent and below said abutment members to serve as vertical alignment fixtures and to coact with said abutment members to limit tipping movement of said heat exchanger assembly.

7. A warm air furnace comprising a heavy heat exchanger assembly having provision for the transfer of heat from internally combusted fuel to air in contact with the external surface thereof and a curved bottom wall lying on an arc about a point along the vertical centerline of said assembly, said assembly being of substantially equal proportions on each side of said vertical centerline so that the center of gravity thereof lies along said vertical centerline, and means to support and align said heat exchanger assembly in the furnace comprising a frame including a vertical plate having a V-shaped upper edge adapted to cradle said curved bottom wall with the sides of the V-shaped edge tangentially contacting said curved bottom wall.

8. A warm air furnace comprising a heavy heat exchanger assembly having provision for the transfer of heat from internally combusted fuel to air in contact with the external surface thereof and a curved bottom wall lying on an arc about a point along the vertical centerline of said assembly, said assembly being of substantially equal proportions on each side of said vertical centerline so that the center of gravity thereof lies along said vertical centerline, and means to support and align said heat exchanger assembly in the furnace comprising a frame including a plurality of vertical plates each having a V-shaped upper edge adapted to cradle said curved bottom wall with the sides of the V-shaped edge tangentially contacting said curved bottom wall.

9. A warm air furnace comprising a heavy heat exchanger assembly having provision for the transfer of heat from internally combusted fuel to air in contact with the external surface thereof and a curved bottom wall lying on an arc about a point along the vertical centerline of said assembly, said assembly being of substantially equal proportions on each side of said vertical centerline so that the center of gravity thereof lies along said vertical centerline, and means to support and align said heat exchanger assembly in the furnace comprising a frame including a vertical plate having a V-shaped upper edge adapted to cradle said curved bottom wall with the sides of the V-shaped edge tangentially contacting said curved bottom wall, and a pair of upright, rigid members each extending above a point of contact of said plate and bottom wall and terminating adjacent a portion of said assembly to serve as a vertical alignment fixture and tip-limiting abutment.

10. A warm air furnace comprising a heavy heat exchanger assembly having provision for the transfer of heat from internally combusted fuel to air in contact with the external surface thereof and a curved bottom wall lying on an arc about a point along the vertical centerline of said assembly, said assembly being of substantially equal proportions on each side of said vertical centerline so that the center of gravity thereof lies along said vertical centerline, and means to support and align said heat exchanger assembly in the furnace comprising a frame including a plurality of vertical plates each having a V-shaped upper edge adapted to cradle said curved bottom wall with the sides of the V-shaped edge tangentially contacting said curved bottom wall, and a plurality of pairs of upright, rigid members, each pair of members extending above the points of contact of one of said plates and the bottom wall contiguous thereto and terminating adjacent portions of said assembly to serve as vertical alignment fixtures and tip-limiting abutments.

11. A warm air furnace comprising a heavy heat exchanger assembly having provision for the transfer of heat from internally combusted fuel to air in contact with the external surface thereof and a curved bottom wall lying on an arc about a point along the vertical centerline of said assembly, said assembly being of substantially equal proportions on each side of said vertical centerline so that the center of gravity thereof lies along said vertical centerline, a horizontally extending tie-rod at each side of said heat exchanger and externally thereof, and means to support and align said heat exchanger assembly in the furnace comprising a frame including a vertical plate having a V-shaped upper edge adapted to cradle said curved bottom wall with the sides of the V-shaped edge tangentially contacting said curved bottom wall, and a pair of upright, rigid members each extending above a point of contact of said plate and bottom wall and terminating closely adjacent and below one of said tie-rods to serve as a vertical alignment fixture and to coact with said tie-rod to limit tipping movement of said heat exchanger assembly.

12. A warm air furnace comprising a heavy heat exchanger assembly having provision for the transfer of heat from internally combusted fuel to air in contact with the external surface thereof and a curved bottom wall lying on an arc about a point along the vertical centerline of said assembly, said assembly being of substantially equal proportions on each side of said vertical centerline so that the center of gravity thereof lies along said vertical centerline, a horizontally extending tie-rod at each side of said heat exchanger and externally thereof, and means to support and align said heat exchanger assembly in the furnace comprising a frame including a plurality of vertical plates each having a V-shaped upper edge adapted to cradle said curved bottom wall with the sides of the V-shaped edge tangentially contacting said curved bottom wall and a plurality of pairs of upright, rigid members, each pair of members extending above the points of contact of one of said plates and the bottom wall contiguous thereto and terminating closely adjacent and below said tie-rods to serve as vertical alignment fixtures and to coact with said tie-rods to limit tipping movement of said heat exchanger assembly.
